UNITED STATES PATENT OFFICE.

WILLIAM A. SMITH, OF DENVER, COLORADO, ASSIGNOR TO THE DENVER ROCK DRILL MANUFACTURING COMPANY, OF DENVER, COLORADO, A CORPORATION OF DELAWARE.

FLUID-OPERATED MOTOR.

1,257,753.

Specification of Letters Patent. Patented Feb. 26, 1918.

Application filed December 27, 1916. Serial No. 139,140.

To all whom it may concern:

Be it known that I, WILLIAM A. SMITH, a citizen of the United States, residing at Denver, in the county of Denver and State 5 of Colorado, have invented certain new and useful Improvements in Fluid-Operated Motors, of which the following is a specification.

The present invention relates more particularly to valveless motors of the type in which the piston directly controls the distribution of the motive fluid and its exhaust.

The object is to provide simple means of a novel and effective character.

15 The preferred embodiment of the invention is illustrated in the accompanying drawings, wherein:—

Figure 1 is a longitudinal sectional view through a rock drill, showing the motor as 20 a part thereof.

Figs. 2 and 3 are cross sectional views on the lines 2—2 and 3—3 of Fig. 1.

Fig. 4 is a detail longitudinal sectional view through the motor and taken on the 25 line 4—4 of Fig. 2.

Fig. 5 is a detail sectional view on the line 5—5 of Fig. 4.

Similar reference numerals designate corresponding parts in all the figures of the 30 drawings.

In the embodiment illustrated, a cylinder member is employed, comprising a body 6 having a piston chamber 7 therein. The rear end of said piston chamber is closed by 35 a rear head block 8 and a front head block 9, the latter containing a tappet 10 that projects into the piston chamber. A reciprocating hammer piston 11 is located in the chamber 7 and is arranged to strike the rear 40 end of the tappet 10, as will be readily understood.

Motive fluid is supplied from any suitable source through a nipple 12 that communicates with a valve casing 13 formed upon 45 one side of the head block 8. A rotary taper valve 14 of well known form is located in the casing 13 and controls the supply of fluid to a port 15 formed in the head block and communicating with branches 16 50 also formed in said head block. These branches in turn are in communication with longitudinally disposed supply channels 17 formed in opposite sides of the cylinder body

and that terminate at their front ends in supply ports 18 that open into the piston 55 chamber 7 between its ends.

The piston 11 is provided in its opposite sides with longitudinally disposed distributing channels 19 that are in constant communication with the supply ports 18. These 60 channels, as shown in Fig. 1, terminate short of the ends of the piston hammer, and their ends are alternately movable into communication with recesses 20 formed in the cylinder body walls in line with the ports 18. 65 The recesses are longer than the distance between the ends of the distributing channels 19 and the ends of the hammer piston.

Exhaust permitting means is provided, comprising oppositely disposed front and 70 rear sets of ports 21 that are in communication with exhaust passageways 22 formed in opposite walls of the piston body 6 and opening to the atmosphere. These exhaust ports 21 are out of line with the supply ports 75 18 and recesses 20.

In order to maintain the piston hammer to a fixed path of movement, said hammer is provided with longitudinally disposed feather receiving grooves 23 that terminate 80 short of the front end of the hammer piston and preferably open through the rear end thereof. These grooves are disposed out of line with both the exhaust ports 21 and the supply ports 18, and engaged therein are 85 suitable feathers 24 fixed in the cylinder body. The feathers, by thus holding the piston, serve to maintain the distributing channels 19 in proper relation to the supply ports 18 and recesses 20, and by preventing 90 the turning of the piston hammer, they prevent improper relations between the distributing channels 19 and the exhaust ports 21.

It is believed that the operation of the device will be readily understood. When 95 motive fluid is admitted to the port 15, it will pass through the branches 16 into the passageways 17, and thus enter through the ports 18 into the distributing channels 19. These channels will alternately direct the 100 motive fluid to the front and rear ends of the piston chamber 7, and consequently against the opposing front and rear faces of the piston hammer, causing the reciprocation of the same. When motive fluid is 105 thus admitted to one end of the piston cham-

ber, the exhaust ports at the other end will be uncovered by the piston permitting the exhaust of the fluid from the opposite end.

From the foregoing, it is thought that the 5 construction, operation and many advantages of the herein described invention will be apparent to those skilled in the art, without further description, and it will be understood that various changes in the size, 10 shape, proportion and minor details of construction, may be resorted to without departing from the spirit or sacrificing any of the advantages of the invention.

Having thus fully described my invention, 15 what I claim as new, and desire to secure by Letters Patent, is:

1. In apparatus of the character set forth, the combination with a cylinder member comprising a body having a piston chamber and a head block, of means for supplying motive fluid to the cylinder member, comprising an inlet having branches in the head block and passageways in the cylinder body leading from the branches and having supply ports opening into the piston chamber, a piston operating in the chamber, said piston having distributing channels in constant communication with the ports and said channels alternately opening into the piston 25 chamber on opposite sides of the piston accordingly as said piston reciprocates, means permitting the exhaust from the piston chamber on opposite sides of the piston, said exhaust permitting means being controlled 30 by the piston, the distributing channels of said piston overrunning or passing the transverse planes of the exhaust permitting means while maintaining communication with said supply ports but being out of line 35 with said exhaust permitting means, and means for maintaining the piston to a fixed path to maintain the proper relation of the ports and channels and prevent improper relations between the channels and exhaust 40 45 permitting means.

2. In apparatus of the character set forth,

the combination with a cylinder member comprising a body having a piston chamber and a head block, of means for supplying motive fluid to the cylinder member comprising a valved controlled inlet in the head block having branches in said head block and passageways communicating with the branches, said passageways extending longitudinally in the cylinder body walls and terminating in supply ports that open into the piston chamber between its ends, exhaust permitting means in the cylinder wall out of longitudinal line with the supply ports, said cylinder body having internal recesses in its end portions in substantial line with the supply ports, the piston having longitudinally disposed channels terminating short of the ends thereof, said channels being constantly in communication with the supply ports and alternately communicating with the recesses, and said piston alternately covering and uncovering the exhaust permitting means, the distributing channels overrunning or passing the transverse planes of the exhaust permitting means but being out of line therewith while maintaining communication with the said supply ports, a feather receiving groove in the piston terminating short of one end thereof and being out of line with the distributing ports and exhaust permitting means, and a feather carried by the cylinder body and engaged in the feather receiving groove to hold the piston to a fixed path and thus maintain the distributing channels in proper association with the supply ports and recesses while preventing improper associations between the channels and exhaust permitting means.

In testimony whereof, I affix my signature in the presence of two witnesses.

WILLIAM A. SMITH.
